UNITED STATES PATENT OFFICE.

JAMES CLAYTON, OF BROOKLYN, NEW YORK.

IMPROVEMENT IN AIR-COMPRESSORS.

Specification forming part of Letters Patent No. 222,014, dated November 25, 1879; application filed September 19, 1879.

To all whom it may concern:

Be it known that I, JAMES CLAYTON, of Brooklyn, in Kings county, and State of New York, have invented new and useful Improvements in Air-Compressors, of which the following is a specification.

In working air-compressors a great amount of heat is generated within the air-cylinders, and in order to keep the cylinders cool they are commonly provided with a jacket, through which water is circulated. As the air is at its greatest pressure at the end of the stroke of the air-compressing piston, it follows that the cylinder becomes hottest near the ends, and the expansion causes the diameter at the ends to increase, leaving the diameter of the cylinder least at the middle. From this cause the air-compressing piston will bind at the middle of the stroke and leak at the ends.

The object of my invention is to provide for maintaining an even temperature of the cylinder throughout its length, so that the rate of expansion shall be uniform, and variations in the diameter of the cylinder at different points be prevented.

To this end my invention consists in an air-compressing cylinder, having a water-jacket, the water-inlets of which are at or near the two ends of the cylinder, and the water-outlet of which is at or near the middle of the length of the cylinder. When such cylinder is arranged horizontally its water-inlets will be at the top, with passages leading down each side thereof, thence towards the middle and up each side to the water-outlet.

In the accompanying drawings, Figure 1 represents a longitudinal section through an air-compressing cylinder embodying my invention; Fig. 2, a transverse section thereof on line xx , Fig. 1; and Fig. 3, a plan, a portion of the cylinder itself being broken away to show the exterior of the lining with its passages.

Similar letters of reference designate corresponding parts in all the figures.

A designates a double-acting horizontal air-compressing cylinder, and B the heads thereof, one of which is provided with a stuffing-box, a , through which the piston-rod may pass. C designates valve-chests upon the top of the cylinder, which may contain inlet and outlet

valves of any desired kind, but which, as they form no part of the present invention, are not here represented.

D designates a removable lining, inserted in the cylinder, and provided at each end with flanges or ribs b , for centering it properly in the cylinder. This lining is so constructed as to form a jacket around the cylinder for the circulation of water or any other cooling-agent.

E designates inlet-pipes for the water or other cooling-agent, and F an outlet-pipe therefor.

When the air-compressing cylinder is placed horizontally, as here represented, the portion which will become most highly heated is at the ends and upon the top, as the hot air rises and is discharged at the top of the cylinder.

When the cold water or other cooling-agent enters at the pipes E, it enters extended chambers G, extending nearly half the length of the cylinder, and from thence passes each side of the cylinder through openings c , down passages H, to the bottom of the cylinder, whence it passes longitudinally through openings d , to a central passage, I, and thence to the outlet-pipe F.

The several passages are here formed by providing the lining D with ribs or flanges f , extending upon its exterior, and broken away so as to form openings for the passage of water at the proper points.

In lieu of the removable lining, however, the several passages might be made within the casting of the cylinder.

It will be seen that the water upon entering, when it is coldest, comes in contact with the warmest parts of the cylinder and abstracts more heat from such portions than it does from the middle portions; hence the temperature of the cylinder will be more nearly uniform throughout its length.

What I claim as my invention, and desire to secure by Letters Patent, is—

1. An air-compressing cylinder, having a water-jacket, the water-inlets of which are at or near the two ends of the cylinder, and the water-outlet of which is at or near the middle of the length of the cylinder, substantially as specified.

2. A horizontal air-compressing cylinder

having a surrounding water-jacket, the water-inlets of which are at or near each end of the cylinder and at the top thereof, and in which are passages leading from the said inlets down each side of, and thence toward the middle of the length of the cylinder, and up each side thereof, to a water-outlet near the middle of the length thereof, substantially as and for the purpose specified.

3. The horizontal air-compressing cylinder A, having a surrounding water-jacket compos-

ing the extended chambers G, on top and at each end of the cylinder, to which water is admitted through the inlet E, the passages H leading therefrom, down each side of the cylinder, and the passage I leading up each side of the cylinder to the outlet F, substantially as and for the purpose specified.

JAMES CLAYTON.
